IVAR L. LANGVAND, OF BARBERTON, OHIO, AND HOWARD J. KERR, OF WESTFIELD, NEW JERSEY, ASSIGNORS TO THE BABCOCK & WILCOX COMPANY, OF BAYONNE, NEW JERSEY, A CORPORATION OF NEW JERSEY

WATER TUBE BOILER

Application filed September 30, 1929. Serial No. 396,041.

This invention relates to a water tube boiler that is provided with a plurality of transverse drums connected by banks of tubes with baffles for guiding the gases across the tubes from the furnace of the boiler.

The invention will be understood from the description in connection with the accompanying drawings in which Fig. 1 is a vertical section along the line 1—1 of Fig. 2; Fig. 2 is a section, one-half being along the line 2—2 of Fig. 1 and the other half along the line 2'—2' of Fig. 1; Fig. 3 is a side view of the boiler; and Fig. 4 is a vertical section showing a modification.

In the drawings, reference character 1 indicates a transverse drum at the upper rear end of the boiler. A transverse drum 2 is located at the upper portion of the front end of the boiler at a lower elevation than the drum 1. Lugs or brackets 3 are provided at the ends of the drums 1 and 2 by means of which these drums are supported upon a steel frame-work 4 on the outside of the boiler setting. The supporting frame-work or structure comes below the level of the upper drums of the boiler and comprises horizontal beam members supported on columns near the end of the boiler setting.

A plurality of steam circulating tubes 5 that are straight for the major portion of their lengths connects the drums 1 and 2, these tubes being bent at their ends to enter the drums radially. A drum 6 is located at the rear of the furnace at a lower level than the other drums and is connected by a plurality of water circulating tubes 7 to the drum 1 and a bank of inclined steam generating tubes 8 to the drum 2, these tubes also being straight for the major portions of their lengths, but bent at the ends to enter the respective drums radially.

A furnace 9 provided with a grate 10 is located below the tubes 8 and baffles are provided for directing the flow of hot products of combustion from the furnace 9 across the bank of tubes 8 and in contact with the steam circulators 5 and water circulators 7. The lowermost tubes in the bank 8 are bent around to protect the drum 2 from the heat of the furnace. A baffle 12 extends from the upper

side of the drum 6 approximately along the middle of the bank of tubes 8 somewhat less than one-half of the length of the row of tubes. A transverse baffle 13 extends from the end of the baffle 12 upwardly across the tubes of the bank 8 above the baffle 12 to the lowermost row of tubes 5. A baffle 14 extends from the lower side of the drum 1 in an inclined direction in front of the tubes 7 to the uppermost row of tubes 8, the lower end of said baffle being kept in place by means of lugs 14' attached to the uppermost row of tubes 8. A tapering gas path is thus provided for the gases from the furnace as they flow over the tubes. An outlet 15 provided with a damper 16, that may be operated by a lever 17 on the outside of the setting, is provided in the rear wall of the furnace behind the upper end of the tubes 7.

Staggered deflector baffles 20 that are spaced apart are provided upon some of the rows of tubes 8 to control the gas flow across these tubes and a plurality of similar deflector baffles 21 extend along the upper side of the lowermost row of tubes 5 from the drum 2 to the baffle 13. A vertically disposed baffle 22, extending longitudinally of the drum 1, is located in front of the exit ends of the tubes 5 in the drum 1.

A feed water inlet pipe 23 enters the drum 1 and the outlet end thereof terminates a short distance from the lower side of the drum 1. A baffle 24 is provided in the drum 1 between the lower end of the pipe 23 and the baffle 22. A steam outlet 25 is provided at the top of the drum 1 and is connected to the dry pipe 26 in the steam space of this drum. A valved outlet pipe 27 leads from the lower side of the drum 6.

The rear wall 28 of the furnace extends upwardly to shield the side of the drum 6 and lagging material 29 is provided between the end of the wall 28 and the drum 6 to prevent gas leakage by this drum. A dust chamber 30 is provided between the wall 28 and the rear wall of the boiler setting from which soot and dust that accumulate may be taken out through the door 31. The roof 32 of the boiler setting extends along the upper side of the upper row of tubes 5 and around the 100

drums 1 and 2. Safety valves 33 may be provided on the drum 1.

The drums and tubes are supported by means of the steel supports outside of the setting, the drums 1 and 2 being supported, leaving the drum 6 to move due to expansion and contraction of the banks of tubes 7 and 8. The deflector baffles 20 and 21 control the gas flow area for the gases flowing through the tapering pass across the tubes 8, along the tubes 5, across some of the rows of tubes 8 and then across the tubes 7 through the outlet 15.

Feed water from the drum 1 and water that may enter the drum 1 along with the steam from the tubes 5 passes downwardly through the tubes 7 into the drum 6, thence through the tubes 8 into the drum 2 as a mixture of steam and water. The hot gases contacting with the tubes 5 exert a drying action on the steam that passes from the drum 2 to the drum 1, and the baffle 22 in the drum 1 aids in separating the steam and water that enters this drum from the tubes 5. The hot gases contacting with the tubes 7 heat the water entering the drum 6. The ends of the drums 1 and 2 extend beyond the walls of the boiler setting, but the drum 6 is entirely within the boiler setting with its ends including the head seams received in recesses in the walls of the setting but out of contact with the walls of the recesses. The drums 1, 2 and 6 may each be made with a single longitudinal joint so located as to be out of the path of the hot gases. The head seams for the drums 1 and 2 lie outside of the boiler setting and are thus protected from the hot gases. The head seams for drum 6 are also protected due to their being received in recesses in the walls but without interfering with the movement of the drum due to expansion and contraction of the boiler parts. The normal water level is maintained in the drum 1 and a water gauge may be connected to this drum to indicate the water level.

In the modification shown in Fig. 4, the baffles 20 and 21 shown in the other illustrative embodiment of the invention and the two lower rows of the steam circulating tubes 5 are omitted. The baffle 14 is extended downwardly, as indicated at 14" along the upper row of tubes 8 for some distance toward the drum 6. The upper edge of the baffle 13 is extended upwardly a short distance so as to have the gas path above this baffle of substantially the same area as in the other modification. The baffle 13 may be supported from the tubes 5 by means of the supports 35.

We claim:—

1. In a low head water tube steam boiler, a furnace, a steam offtake drum, a submerged intermediate drum located below the water level of the offtake drum and at the opposite side of the furnace, horizontally arranged

steam circulators leading from the top of the intermediate drum to the steam space of the offtake drum and constituting the only direct connection between those two drums, a lower drum positioned at the offtake drum end of the furnace, a main bank of inclined steam generating tubes forming the roof of the furnace and directly connecting the lower and intermediate drums, and a bank of water circulator tubes directly connecting the offtake drum and the lower drum so that the horizontal distance between the drum centers of the main bank of tubes is much greater than the vertical distance, the steam circulators constituting a steam pass in which the steam generated in the main bank of tubes is subjected to drying action on its way to the offtake drum, the tubes of the water circulator bank being bent away from a line connecting the centers of the offtake and lower drums to provide a lower drum tube seat portion extended at the top of that drum for the securement of the bent ends of the tubes of the main bank therein.

2. In a low head water tube steam boiler, a boiler setting, a furnace, a steam offtake drum, a lower drum at a level beneath that of the offtake drum, water circulators connecting said drums, an intermediate submerged drum at the end of the setting opposite the offtake drum, horizontal steam circulator tubes having inlets leading from the top of the intermediate drum and outlets communicating with the steam space of the offtake drum, a deep main bank of steam generating tubes directly connecting the lower and intermediate drums and positioned at a small angle to the horizontal so as to occupy the major part of the boiler space between the center line connecting the offtake and intermediate drums and the center line connecting the lower and intermediate drums, and baffle structures so arranged as to compel the furnace gases to pass in a first gas pass in contact with several lowest rows of tubes of the main bank over their entire length and then from the main bank of tubes directly to the steam circulators and thence again across the steam circulators and some of the tubes of the main bank to the lower ends of the water circulators, the steam circulators providing all of the direct communication between the offtake and intermediate drums in order that there be no provision for water movement directly from the intermediate drum to the offtake drum.

3. In a low head water tube steam boiler, a boiler setting, a furnace, a steam offtake drum, a lower drum at a level beneath that of the offtake drum, water circulators connecting said drums, an intermediate submerged drum at the end of the setting opposite the offtake drum, horizontal steam circulator tubes having inlets leading from the top of the intermediate drum and outlets com-

- municating with the steam space of the off-take drum, a deep main bank of steam generating tubes directly connecting the lower and intermediate drums, and positioned at a small angle to the horizontal so as to occupy 5 a line connecting the centers of the offtake and lower drums to provide a lower drum tube seat portion extended at the top of that drum for the securement of the bent ends of the tubes of the main bank therein. 70
- the major part of the boiler space between the center line connecting the offtake and intermediate drums and the center line connecting the lower and intermediate drums, 10 IVAR L. LANGVAND.
HOWARD J. KERR.
- gas pass boundary baffle structures so arranged as to compel the furnace gases to pass in a first gas pass in contact with several lowest rows of tubes of the main bank over their entire length and then from the main 15 75
- bank of tubes directly to the steam circulators and thence in a second gas pass again across the steam circulators and some of the tubes of the main bank to the lower ends of the water circulators, and spaced gas distribution 20 80
- baffles positioned upon the tubes in the first gas pass so as to obstruct the passages between some of the adjacent tubes while leaving adjacent similar passages unobstructed in horizontal rows of the tubes, the distribution 25 85
- baffles in successive horizontal rows alternating with respect to each other, the steam circulators providing all of the direct communication between the offtake and intermediate drums in order that there be no provision 30 90
- for water movement directly from the intermediate drums to the offtake drum. 95
4. In a low head water tube steam boiler, a furnace, a steam offtake drum, an intermediate water drum located below the level of 35 100
- the offtake drum and at the opposite side of the furnace, horizontally arranged steam circulators leading from the top of the intermediate drum to the steam space of the offtake drum and constituting the only direct 40 105
- connection between those two drums, a lower drum positioned at the offtake drum end of the furnace, a main bank of horizontally inclined steam generating tubes directly connecting the lower and intermediate drums, 45 110
- a plurality of spaced gas distribution baffles positioned upon one or more horizontal rows of the tubes of the main bank so as to obstruct the passage of gas between some of the adjacent tubes while leaving adjacent similar 50 115
- passages unobstructed in horizontal rows of the tubes to form gas passages, said baffles acting to uniformly distribute over the whole length of the main bank of tubes within the gas pass a gas flow which is transverse to the 55 120
- tubes of the main bank, a bank of water circulator tubes directly connecting the offtake drum and the lower drum so that the horizontal distance between the drum centers of the 60 125
- drums for the main bank of tubes is much greater than the vertical distance, the steam circulators constituting a steam pass in which the steam is subjected to drying action on its way to the offtake drum, the tubes of the 65 130
- water circulator bank being bent away from
